UNITED STATES PATENT OFFICE

GUY LYNN ROSEBROOK, OF ROSELLE PARK, NEW JERSEY, ASSIGNOR TO THE J. G. BRILL COMPANY, OF PHILADELPHIA, PENNSYLVANIA, A CORPORATION OF PENNSYLVANIA

DESIGN FOR A SERVICE BUILDING

Application filed June 13, 1931. Serial No. 40,189. Term of patent 3½ years.

To all whom it may concern:

Be it known that I, GUY LYNN ROSEBROOK, a citizen of the United States, residing in Roselle Park, Union County, New Jersey, have invented a new, original, and ornamental Design for Service Buildings, of which the following is a specification, reference being had to the accompanying drawings, forming part thereof, in which—

Fig. 1 is a front elevation of the building;

Fig. 2 is an elevation of the right side of the building; and

Fig. 3 is a sectional plan view.

The design of the rear elevation of the building is similar to the front elevation, and the design of the left side of the building is similar to the right side.

I claim:

The ornamental design for a service building, substantially as shown and described.

GUY LYNN ROSEBROOK.
